(57) **CLAIM**

We claim the ornamental design for a combined tray and lid, as shown and described.

DESCRIPTION

FIG. 1 is a perspective view of the combined tray and lid; FIG. 2 is a top plan view of the combined tray and lid of FIG. 1;

FIG. 3 is a bottom plan view of the combined tray and lid of FIG. 1;

FIG. 4 is a right side elevation view of the combined tray and lid of FIG. 1, the left side elevation view being identical thereto; and,

FIG. 5 is a front side elevation view of the combined tray and lid of FIG. 1, the back side elevation view being identical thereto.

Portions of the figures shown in broken lines form no part of the claimed invention.

1 Claim, 3 Drawing Sheets
